ATTORNEY

UNITED STATES PATENT OFFICE

1,920,899

HAIRCLOTH HOLDER

William L. Sullivan, Pasadena, Calif.

Application May 27, 1932. Serial No. 613,980

3 Claims. (Cl. 24—243)

My present invention has reference to a clip for holding hair cloths around the neck of a person being operated upon by a barber or an artist in beauty shops and the object of the invention is to dispense with pins or analogous devices which pierce the garment and which are apt to inflict injury to the person upon whom the cloth is applied and further to produce a clip which can be easily and quickly applied to properly hold the folds of the cloth together and which also may be readily and quickly detached from the cloth.

To the attainment of the foregoing the invention consists in the improvement hereinafter described and definitely claimed.

In the drawing:

Figure 1 is a perspective view illustrating the application of the improved clip.

Figure 2 is an approximately central longitudinal sectional view through the improvement.

Figure 3 is a transverse sectional view approximately on the line 3—3 of Figure 2.

Figure 4 is a view of a blank of the spring plate from which the body of the clip is formed.

As disclosed by Figure 4 of the drawing the body of the clip is constructed from a single strip of suitable spring metal 1, preferably of steel and which in all events is strong, durable and sanitary. From both of its ends the inner

face of the strip 1 is grooved longitudinally, a single centrally arranged and longitudinally extending groove 2 being provided from one of said ends, and the other end is provided with two spaced longitudinally extending grooves 3, respectively.

The end provided with the single groove 2 is bent and rounded upon itself from a transverse score line 4 (Figure 4), while the end provided with the spaced pair of grooves is bent from the central portion of the body 5 of the strip first upon the transverse score line 6 and then on the second and outer transverse score line 7 (Figure 4). These bent portions provide the strip with an inner spring jaw 8 and an outer spring jaw 9, and the end of the spring

jaw 9 is tapered or rounded outwardly, as at 10. The grooved portions of the respective jaws afford confronting ribs, and the body of the strip is formed with a rounded enlargement 11 that is interiorly threaded and has screwed therein the stem of a short headed bolt that has a knurled head 12. The head is received in the groove 2 of the inner jaw 8 and by adjusting the said

screw the jaw 8 may be forced toward the outer jaw 9.

As disclosed by the drawing the clip may be readily slipped over the folded rear portions of a neck cloth 13 and by adjusting the screw 12 the jaw 8 is forced toward the jaw 9 to tightly grip the cloth 13 between the ribs and grooves afforded on the confronting ends of the jaws. Ordinarily the screw 13 may be dispensed with as the jaws exert a sufficient spring action toward each other as to tightly grip the cloth 13 therebetween.

By reference to Figure 2 of the drawing it will be noted that the rounded portion between the body 5 and the jaw 9 protrudes, as at 16, toward the outer face of the said jaw and this protruding portion also affords a contact element for the cloth 13.

Having described the invention, I claim:

1. A hair cloth holder comprising a clip formed from a single piece of material bent upon itself to provide a body, an inner jaw and an outer jaw, said inner jaw being grooved to provide the jaw with a central rib, the said outer jaw being grooved to provide the latter with spaced end ribs, and a movable member extended through the body and contacting with the inner jaw to force the latter toward the outer jaw.

2. A hair cloth holder comprising a clip formed from a single piece of spring metal bent upon itself from adjacent its outer ends to provide a body an inner jaw and an outer jaw, said outer jaw having its end rounded outwardly and both of the jaws being grooved to provide respectively central and end ribs, and a knurled screw threaded through the body to contact with the groove in the inner jaw to force the inner jaw toward the outer jaw.

3. A hair cloth holder comprising a clip formed from a single piece of spring metal bent upon itself from adjacent its outer ends to provide a body an inner jaw and an outer jaw, said outer jaw having its end rounded outwardly and both of the jaws being grooved to provide respectively central and end ribs, and a knurled screw threaded through the body to contact with the groove in the inner jaw to force the inner jaw toward the outer jaw, and the rounded connecting portion between the body and the outer jaw being protruded outwardly.

WILLIAM L. SULLIVAN.
